UNITED STATES PATENT OFFICE.

EVELYN M. McCAIN, OF CANTON, OHIO.

DESIGN FOR A GARMENT.

54,108.

Specification for Design.

Patented Nov. 4, 1919.

Application filed December 28, 1918. Serial No. 268,776. Term of patent 7 years.

To all whom it may concern:

Be it known that I, EVELYN M. McCAIN, a citizen of the United States, residing at Canton, in the county of Stark and State of Ohio, have invented a new, original, and ornamental Design for a Garment, of which the following is a specification, reference being had to the accompanying drawing, forming part thereof.

In the drawings:

Copies of this patent may be obtained for five cents each, by addressing the "Commissioner of Patents, Washington, D. C."

Fig. 2 is a perspective view from the rear.

I claim:

The ornamental design for a garment, substantially as shown.

EVELYN M. McCAIN.

Witnesses:

J. A. BISHOP,
SYLVIA BORON.
